UNITED STATES PATENT OFFICE.

JOHN SEWELL STAPLES, OF LONDON, ENGLAND.

CARBURETOR FOR EXPLOSION ENGINES.

Application filed December 6, 1917. Serial No. 205,862.

To all whom it may concern:

Be it known that I, JOHN SEWELL STAPLES, a subject of the King of England, residing in London, England, have invented 5 certain new and useful Improvements in Carburetors for Explosion Engines, of which the following is a specification.

This invention relates to improvements in carburetors for explosion engines. 10 In my improved carburetor a number of fuel orifices or jets formed in a horizontal member are closed or opened by the movement upon said member of the edge of a throttle slide, the position given to the slide 15 allowing a greater or less number of said orifices or jets to be brought into action. At full opening of the slide suction is exerted on the full range of jets and as there is then no obstruction or restriction of the 20 size of the suction conduit, the greatest possible amount of fuel is supplied. At slow speeds of the engine a certain number of the fuel orifices are closed by the slide and the suction is exerted to the fullest possible 25 extent on the remaining uncovered jets, allowing a mixture to be formed at a speed of the engine which with known carburetors would not be sufficient to pick up the necessary fuel.

30 I further provide an air governing slide adjacent the throttle slide and movable transversely thereto, the size of the air supply opening being governed by the relative movement of the two slides and proportional 35 to the fuel supply; the air current flows transversely across the horizontal row of fuel jets causing an intimate mixture to be produced.

40 A further feature of my invention consists in improved means for controlling the supply of fuel to the jets, and a further feature consists in the provision of a heating member for heavy fuel arranged adjacent the fuel jets, whereby said heavy fuel 45 is volatilized as it passes through the fuel jets, and choking of the jets is prevented.

These and other features of my improved carburetor will be hereinafter fully described and referred to in the appended 50 claims.

The annexed drawings illustrate an example of construction of the improved carburetor adapted for two kinds of fuel.

Figure 1 is a plan view.

55 Figure 2 is a section on line A—A of Fig. 1.

Figure 3 is a section on line B—B of Fig. 2 and

Figure 4 is a detail view illustrating means for changing the fuel. Fig. 2^a is a 60 perspective view of the fuel jets.

Further I provide means for heating the fuel adjacent the fuel orifices and means for heating the air supply.

The improved carburetor comprises a flat 65 member 1 having a rectangular aperture 2, a water or gas heated tubular body or extension 3 being provided for the connection of the carburetor to the induction pipe 70 of the engine. This body has a circular 70 opening 4 of the same diameter as that of the induction pipe and has a flange 5 for the attachment to the induction pipe. The flat member 1 supports the jet forming members, throttle slides and the like. Integral 75 with or connected to the flat member 1 and adjacent the fuel orifices 6 is a conduit or 80 conduits 7 for the passage of the exhaust gases or hot water for heating the fuel adjacent the said orifices. This conduit is provided at each end with a union 43 and 44 respectively for the connection of the pipes conveying the heating fluid. By removing these unions the conduit 7 can be easily 85 cleaned out. The member 1 is also provided on its face 15^c with a fuel duct 8 communicating with an ordinary float chamber or chambers. In the example illustrated two float chambers 9, 10 are used, one for instance for petrol and the other for paraffin, these chambers being connected to the member 1 by arms 11, 12, as illustrated in Fig. 1, or in any other suitable manner.

Against the face of the member 1 a plate 13 is mounted having a ground face to make 95 an air tight joint therewith and provided on this face with serrations extending from the upper edge of said plate 13 to the aforesaid fuel duct 8 so that a series of parallel jets 6 are formed substantially on a line 100 with the bottom of the rectangular aperture 2 and extending along the whole width thereof. These jets 6 are normally covered and closed by a horizontally movable throttle slide 14 of dovetail section adapted to 105 slide against the surface 15^a of the member 1 across the aperture 2 and fitting with its lower edge 15 on the upper inclined surfaces 15^a 15^b of the member 1 and plate 13 so that as this throttle slide is opened, to open or 110 uncover the aperture 2, it progressively uncovers the jets 6 as indicated in Fig. 2. The

slide is dovetailed into the main plate as illustrated in Fig. 2. The throttle slide 14 is held closely in contact with the inclined surfaces 15^a 15^b by means of set screws 15^e 5 acting on an intermediate plate 16 bearing on the throttle slide and further the suction of the engine tends to maintain the slide 14 in contact with the surface 15^d. A vertically sliding plate 17 is arranged behind the throttle slide 14 and is used to regulate the supply of air to produce a good mixture. The bottom edge of the slide 17 abuts on the ledge 18 of the slide 14 when the said slide 17 is in its lowest position, the object being 10 to bring the slide 17 as near as possible into the plane of the fuel jets while at the same time giving sufficient width to the edge 15. The air slide 17 and the throttle slide 14 are operated in any suitable manner. The fuel 15 duct 8 communicates with the two float chambers, the supply of the different fuels being controlled preferably by means of 20 needle valves 19, 20.

Attached to the rear face of the member 1 25 is a doubled walled tubular body 21 heated by the exhaust gases or water circulating in the space 22. 23 and 24 are unions for the connection of the pipes conveying the heating fluid. The end 23^a of the body 21 30 is connected to the member 1 by screws and a flange 24 and is at the end of rectangular shape and has a rectangular opening 23^b to conform with the rectangular aperture 2 of the member 1.

35 The other end 25 of the body 21 is also of rectangular shape but is of flattened section and has a flattened rectangular opening 25^a. 26 is a detachable lid for closing and allowing of cleaning the space 22. 27 is the bell 40 cover of sheet metal which is attached to the body 21, by nuts 28 the screws 29 of which are received in lugs 30 and pass through the lid 26 and the bell cover 27 the rear wall of which is separated from the body 21 by distance pieces 31.

45 The flange 24 forms a guide for the air slide of the carburetor.

The area of opening 25^a is slightly larger than the area of the opening 23^b and the said 50 opening is flattened in section so that the ingoing air, the flow of which is indicated by the arrows, is caused to pass close to the heater walls without being restricted.

This heating device thoroughly and uniformly 55 heats the air while occupying the minimum of space, no heat being radiated to waste from the heater or lost between the point where the air is warmed and the point when it mixes with the fuel.

60 Fig. 4 illustrates on a larger scale the mechanism for actuating the needle valves controlling the supply of fuel from the float chambers 9, 10.

Above the two vertically movable needle 65 valves 19 and 20 (one for each float cham-

ber) is mounted a bracket 32 carrying a rocking fan shaped lever 33 freely mounted on a spindle 34. Also freely mounted on this spindle 34 are two small levers 35, 36, the backs of which are provided with projecting pins 35^a, 36^a, under which the respective curved sides 37^a and 38^a can engage. Attached to the respective levers 35, 36 are two small cables or chains 39, 40, the other ends of which are attached to the respective 75 needle valves 19 and 20.

When the lever 33 is shifted over in the one or other direction by means of the cables 40^a, 40^b, the corresponding lever 35 or 36 will be lifted by the action of the fan shaped 80 lever 33 and will lift the corresponding needle against the action of its spring 41 or 42, thereby allowing fuel to flow from the corresponding float chamber 9 or 10 through the respective conduit 19^a or 19^b to the main 85 duct 8 and so to the fuel nozzles.

For certain types of engines the body 3 can be omitted and the main member 1 connected direct to the engine.

The opening 2 is equal to, or slightly 90 larger than the cross sectional area of the suction conduit, consequently at full opening of the air and jet slides there is no constriction or restriction of the suction conduit.

95 It can be seen that the air supply flows over and at right angles to the horizontal row of fuel orifices and as the suction is always exerted to the fullest possible extent on the jets which are for the time being uncovered, the mixture can be formed at a speed of the engine which with ordinary carburetors would not be sufficient to pick up the fuel.

Also the provision of the heating tube 7 105 adjacent the fuel orifices allows the use of a heavy fuel without choking the fine serrations forming the actual fuel jets, since by placing this heater at the position indicated the fuel is highly heated and volatilized as it 110 passes through the serrations, and choking of the fuel jets is prevented.

What I claim as my invention and desire to secure by Letters Patent of the United States is:—

115 1. A carburetor for explosion engines, comprising a vertical flat member provided with a fuel duct and a rectangular aperture, a plate provided with a series of serrations and fitting closely against said main plate 120 and having its upper edge substantially level with the bottom of said aperture, the said serrations forming with said plate a horizontal row of fuel orifices, a horizontally movable flat slide adapted to progressively cover or uncover said fuel orifices and said aperture, a horizontal ledge extending along the bottom edge of the rear face of said horizontally movable slide, means for adjusting and maintaining the lower edge 125 130

- of said slide on said orifices, means for supplying one or other of a plurality of kinds of fuel through said duct to said orifices, means for heating said flat member adjacent 5 said serrations, a flat slide normally resting with its lower edge on said ledge and movable vertically in contact with the rear face of said horizontally movable slide, and adapted to regulate the size of the aperture 10 uncovered by said horizontal slide and means for conveying air to said aperture, a tubular water or gas heated member conducting air to said aperture connected to the rear face of said main plate, and a bell 15 shaped member surrounding said tubular member so as to cause the air to pass first over the external wall and then over the internal wall of said tubular member to pass through said aperture.
- 20 2. A carburetor for explosion engines comprising a rectangular vertical main member provided with a fuel duct and a rectangular aperture slightly larger in area to the cross sectional area of the induction 25 pipe of the engine, a projecting portion having an inclined upper surface disposed along the lower edge of said main plate, a plate provided with a series of serrations in connection with said duct and fitting closely 30 against said projecting portion and having its upper edge substantially level with the bottom of said aperture and its upper sur-
- face inclined similarly to the upper surface of said projecting portion, the said serrations forming with said plate a horizontal 35 row of fuel orifices, a horizontally movable flat slide of dovetail section adapted to progressively cover or uncover said fuel orifices with its lower edge and said aperture with its front face, a horizontal ledge extending along the bottom edge of the rear face of said horizontally movable slide, means for adjusting said horizontal slide to cause it to bear closely on said inclined surfaces and against said main plate, means 40 for supplying one or other of a plurality of kinds of fuel through said duct to said orifices, a straight conduit extending along the lower edge of said vertical main member, means for conveying heating fluid thereto, 45 a flat slide normally resting with its lower edge on said ledge and movable vertically in contact with the rear face of said horizontally movable slide and adapted to regulate the size of the aperture uncovered by 50 said horizontal slide, and means for conveying air to said aperture.
- In witness whereof I have signed this specification in the presence of two witnesses.

JOHN SEWELL STAPLES.
